By his Attorney s:

W. E. Gray

UNITED STATES PATENT OFFICE.

ALFRED E. DRISSNER, OF CLEVELAND, OHIO, ASSIGNEE TO THE NATIONAL ACME COMPANY, OF CLEVELAND, OHIO, A CORPORATION OF OHIO.

DIRECT DRIVE FOR LEAD CAM DRUMS.

Application filed December 20, 1921. Serial No. 528,640.

To all whom it may concern:

Be it known that I, ALFRED E. DRISSNER, a citizen of the United States, residing at Cleveland, in the county of Cuyahoga and 5 State of Ohio, have invented certain new and useful Improvements in Direct Drives for Lead Cam Drums, of which the following is a specification.

This invention relates to direct driving 10 mechanism for lead cam drums on metal working machines or the like, an object thereof being to provide mechanism for driving the cam drum directly from the worm gear, thereby eliminating the disadvantages 15 residing in driving mechanism heretofore used wherein the drive is indirect, the same being directed from the worm gear through the cam shaft to which the worm gear is keyed or secured and from the cam shaft to the cam drum, the latter also being keyed or secured to the cam shaft. As a result of the present invention therefore, the drive is transmitted directly from the worm gear to the cam drum mounted on the cam shaft instead of indirectly through the cam shaft, as an intermediate means.

Many disadvantages reside in the indirect driving mechanism heretofore used, inasmuch as such drives are troubled greatly by 20 twisting or lost motion between the worm gear and the lead cam drum, which is caused to a considerable extent by the fact that the worm gear drive is indirect. Thus, on account of the existence of twisting and lost motion, the indirect drives previously used 25 impart to the main work slide of the machine an unsteady feed. It is the purpose therefore of the present invention to do away with these disadvantages and as a result 30 a simple, direct driving mechanism is provided, which eliminates all lost motion and springing resulting from keying the worm gear to the cam shaft. And hence, by virtue of this improvement, the main work 35 slide carrying the working tools receives a steady and positive feed from the lead cam drum thereby enhancing considerably the efficiency of the machine.

Furthermore, as a result of the present invention, the construction of the driving mechanism is materially simplified, more durable and serviceable, more efficient and effective in operation, and more economical and easier to manufacture.

55 It is a further object of this invention to

provide a direct driving mechanism for a lead cam drum having safety mechanism between the worm gear and the direct connection between the worm gear and the lead cam drum whereby when undue strain is placed upon the cam shaft due, for instance, to the breaking of a tool or jamming of parts or to a cam catching, the safety mechanism will operate to relieve such stress or strain, and thereby prevent undue breakage of parts.

Other objects of this invention will appear in the following description thereof, reference being had to the accompanying drawing forming a part of this specification, 70 wherein like reference characters indicate corresponding parts in the several views and wherein Fig. 1 is a longitudinal section illustrating the invention; Fig. 2 is a left-hand end view of the improved mechanism; Fig. 75 3 is a right-hand end view of the improved mechanism; and Fig. 4 is a detail sectional view illustrating the safety mechanism.

The present invention in general comprises mechanism for driving the cam drum 80 directly from the worm gear, such drive being directed substantially from the outer circumference of the worm gear to substantially the outer circumference of the main cam drum. Referring to the drawings, it will be 85 seen that the lead or main cam drum 9 is mounted upon the cam shaft 10 and is suitably keyed thereto as at 11 and also pinned thereon as indicated at 12. The cam drum is counterbored at 13 to receive the outwardly 90 flaring or tapered connecting members or bracket arms 14^a of a direct connecting disk or ring-shaped member 14, the members 14^a of the connecting disk being suitably secured to the cam drum by means of screws and 95 pins 15.

The worm wheel 16^a comprises a disk or hub portion 16, which, as will be noted, is loosely mounted upon the cam shaft 10 and hence in no way connected thereto. The 100 worm wheel proper comprises a bronze ring or rim 17 having suitable teeth on its periphery adapted to mesh with the worm 23, the latter being diagrammatically indicated in Fig. 1. It will be noted therefore, that the 105 rim 17 is of such design as to fit on the periphery of the worm wheel and is secured thereto by means of screws 18. The worm gear rim 17 is also constructed to overlap as at 19 a portion of the connecting disk 14 but 110

is not secured to it. The worm wheel or drum 16^a is provided with an inwardly extending flange or hub portion 25, upon which the connecting disk 14 is mounted and the 5 only connection between these parts is in the form of a safety device, which when excessive strain is placed upon the mechanism, will break or shear and thereby relieve the strain.

10 In the present instance the safety mechanism comprises a pair of screws 20 located in the disk 14 and a pair of screws 22 located in the worm wheel 16^a, and registering with the screws 20. The opposed or registering 15 screws are each drilled and counterbored to receive a part of a safety pin 21. In the present instance a pair of safety devices are provided and of course it is understood that one or more, as desired, may be used. Thus, 20 each safety pin 21 is constructed to connect the disk 14 and worm wheel, and is held in position by means of the opposed screws 20 and 22.

During operation, in case a strain greater 25 than these pins will stand is placed upon the mechanism of the machine, the pins will shear and inasmuch as the sole connection between the worm wheel on the one hand and the connecting disk 14 and cam drum 30 9 on the other hand is made by means of the safety pin, the result will be that the worm wheel will rotate relatively to the lead cam drum and cam shaft, the latter therefore being idle until the safety pins are 35 replaced.

Thus, it will be readily seen that when the worm 23 drives the worm wheel or drum 16^a by means of the worm gear rim 17, the cam drum 9 will be driven directly through 40 the direct connection 14. It will be understood of course that the main or lead drum 9 controls the operation of the main slide of the machine, and inasmuch as such mechanism is well known in National Acme machines, a description of the same is not deemed necessary herein, as it constitutes no 45 part of this invention.

Although I have described my invention in its preferred form, it is to be understood 50 that I do not limit myself to the construction herein shown and described, but may make all changes coming within the scope of the appended claims.

I claim as my invention:

55 1. The combination of a rotatable shaft, a drum secured thereto, a worm wheel freely mounted upon said shaft, a connecting disk between said drum and wheel and extending from substantially the outer portion of one 60 to substantially the outer portion of the other, means for connecting said disk to said drum, and safety means for connecting said worm wheel to the disk.

65 2. The combination of a rotary shaft, a driving member freely mounted thereon,

means for continuously rotating said driving member, a driven member secured to the shaft and spaced laterally from said driving member, and a ring shaped connecting member bridging the space between said 70 driving and driven members and fixedly connected to both thereof at a plurality of points about the axis of said shaft.

3. The combination of a rotary shaft, a 75 driving member freely mounted thereon, a driven member secured to the shaft in fixed position and a connecting member located between said driving and driven members, said connecting member having a detachable connection with one of said members and a 80 shearable connection with the other.

4. The combination of a rotary shaft, a 85 driving member freely mounted thereon and comprising a hub and a ring gear fixed thereto, a driven member secured to the shaft, and a connecting member located between said driving and driven members, and connected to each of said members at a plurality of points, the connections with the driving member comprising shearable elements connected to said hub. 90

5. The combination of a rotary shaft, a driving member freely mounted thereon, a driven member secured to the shaft, and a connecting member extending between said 95 driving and driven members and having shearable connection with said driving member, said connecting member being normally fixed to said members.

6. The combination of a rotary shaft, a 100 driving member freely mounted thereon, a driven member secured to the shaft, one of said members having a greater diameter than the other, a ring-shaped connecting member extending between said driving and 105 driven members, and having normally fixed connections therewith, said connections being non-shearable between said connecting member and the driven member, and shearable between said connecting member and 110 driving member.

7. The combination of a pair of spaced 115 rotary members having a common axis of rotation, and means located outside said axis for driving one directly from the other, said means comprising a plurality of outwardly extending arms bridging the space between said members, said arms having fixed connections at both ends with said members, one of the connections being shearable. 120

8. The combination of a rotary shaft, a driven member secured thereto in fixed position, a driving member rotatable independently of said shaft, means directly connecting the members together for simultaneous 125 rotation, said means including a connecting disc fixedly secured to said driven member, and safety mechanism for connecting said disc to said driving member.

9. The combination in a metal working 130

machine of a rotary shaft, a driving wheel freely mounted thereon, a driven cam drum secured to the shaft and spaced laterally from said driving wheel, and means for driving the cam drum from said wheel independently of the shaft and comprising a fixed connecting member embracing the shaft and bridging the space between said wheel and drum.

5

10 10. In a metal working machine the combination of a cam drum and a rotatable wheel having a common axis of rotation, and connecting means located outside said axis for driving one directly from the other, said connecting means comprising a plurality of 15 arms extending between said drum and wheel and normally fixed to both thereof.

Signed at Cleveland, Cuyahoga County, Ohio, this 16th day of December, 1921.

ALFRED E. DRISSNER.
